(57) **CLAIM**

The ornamental design for a vehicle ceiling panel for lighting and air-conditioning, as shown and described.

DESCRIPTION

FIG. 1 is a front view of a vehicle ceiling panel for lighting and air-conditioning showing our new design:

FIG. 2 is a rear view thereof;

FIG. 3 is a right side view thereof;

FIG. 4 is a left side view thereof;

FIG. 5 is a top (plan) view thereof;

FIG. 6 is a bottom view thereof;

FIG. 7 is a top perspective view thereof;

FIG. 8 is a bottom perspective view thereof;

FIG. 9 is a top perspective view of a second embodiment of the vehicle ceiling panel for lighting and air-conditioning shown with a lighting apparatus and an air-discharge opening; and,

FIG. 10 is a bottom perspective view of FIG. 9.

The shading (i.e., dark and light coloring) shown all over the surface of the present ceiling panel in each of the Figures indicates the shape of the three-dimensional surface of the present design.
